F. MANKEY.

MOLDING.

No. 17,138.

Patented Feb. 22, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,138, dated February 22, 1887.

Application filed July 1, 1886. Serial No. 206,870. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding in the form of a band or bar; and it consists in the configuration thereof, as represented substantially herein. On opposite edges of the bar are uniform V-shaped indentations A B. On the face of the bar, and extending diagonally across the same, are grooves or channels C D. The channel C extends from the inner angle of an indentation, as A, on one side of the bar to an outer angle of an opposite indentation, as B, on the other side of the bar. The channel D, parallel to channel C, extends from the inner angle of said indentation B to an outer angle of said indentation A. The two channels C and D and the sides of the indentations A B included between them outline a parallelogram. In said parallelogram and along the center line of the bar may appear counter-

sunk convexities, as E. These, however, may be omitted.

I claim—

1. The design for an ornamental trim or molding, substantially as herein shown and described, which consists in the V-shaped indentations A B on opposite edges and on the face of said trim the inclined parallel channels C D, each of said channels extending from the re-entering angle of a V-shaped indentation on one side to a salient angle of a V-shaped indentation on the other side of said trim.

2. The design for an ornamental trim or molding, substantially as herein shown and described, which consists in the V-shaped indentations A B on opposite edges and on the face of said trim the inclined parallel channels C D, each of said channels extending from the re-entering angle of a V-shaped indentation on one side to a salient angle of a V-shaped indentation on the other side of said trim, and the countersunk convexities E.

FREDERICK MANKEY.
